UNITED STATES PATENT OFFICE.

CHARLES H. CARY, OF WARREN, RHODE ISLAND.

ROTARY ENGINE.

SPECIFICATION forming part of Letters Patent No. 392,538, dated November 6, 1888.

Application filed November 30, 1887. Serial No. 256,572. (No model.)

To all whom it may concern:

Be it known that I, CHARLES H. CARY, a citizen of the United States, residing at Warren, in the State of Rhode Island, have invented 5 a new and useful Improvement in Rotary Engines, of which the following is a specification.

My invention relates to that class of rotary engines in which the rotation of the shaft is derived from reciprocating pistons which operate within the radial piston-chambers of a rotary head; and it consists in the improved construction and arrangement of the chambers of the rotary head and the pistons, and in the improved combination of the same with the 15 shaft and the outer case, as hereinafter fully set forth.

Figure 1 is a vertical section taken transversely of the axis of the engine. Fig. 2 is a vertical axial section of the same. Fig. 3 is an 20 end elevation with the left-hand head of the cylindrical outer case removed. Fig. 4 shows a vertical section of the annular portion of the outer case and an edge elevation of the rotary head. Fig. 5 is a plan view of one of the connecting-arms. Fig. 6 is an edge view of the 25 same. Fig. 7 is a vertical section showing a modification.

In the accompanying drawings, *a* is the cylindrical portion of the outer case, *A*, which is 30 supported by a base, *b*, the said base being provided with a passage, *c*, for the escape of the exhaust-steam or other fluid from the chamber *d* of the outer case. The head *D* of the case is provided with the inwardly-projecting hub *C*, 35 which forms a stationary valve for the surrounding piston-chambers *B B B B* of the rotary head, the said stationary valve being provided with the induction-port *x* and the exhaust-port *y*, the said ports *x* and *y* being 40 preferably arranged diametrically opposite each other.

Within the radially-directed cylindrical chambers *B* of the rotary head *D* are placed the pistons *F*, which upon their inwardly-directed faces are hollowed with the curvature of the periphery of the stationary valve *C*. From a pin or bar, *f*, which extends diametrically across the pistons *F*, connection is made with the arm *g* by means of the connecting-link *h*. 45 The arm *g* is firmly held upon a shaft, *i*, which extends from side to side of the rotary head, and upon one end of the shaft *i* is firmly se- 50

cured the arm *j*, from which connection is made to the eccentrically-located pin *k* at the end of the stationary valve *C*, and a preferable connection is made from the outer ends of the said arms *j* to the fixed eccentric-pin *k* by means of the connecting-rods *m m m m'*, the said connecting-rod *m'* being made with an enlarged hub portion, *n*, provided with a groove, *o*, 60 within which the ends of the rods *m m m* are pivoted by means of the pins *p*. Thus the rod *m'* will alone embrace the eccentric-pin *k*, thereby economizing space and bringing all the connecting-rods in the same plane. 65

The shaft *G* is connected to the rotary piston-head *D* by means of the spider-plate *q*, which is firmly keyed to the said shaft and bolted to the side of the rotary head *D*, the said shaft *G* passing outward through the hub 70 *r* of the head *s* of the outer case.

The stationary valve *C* is made tapering, and the rotary head is made to fit the tapering valve, and the proper adjustment can be made for tightening the joint between the stationary 75 valve and the rotary head by means of the collar *t* on the shaft *G*, the screw-cap *u*, which screws upon the end of the hub *r*, and the adjustable collar *v*, which is held upon the shaft *G* by means of the set-screw *w*. The steam or 80 other operating-fluid can pass through the pipe *H*, and thence to the induction-port *x*, and after actuating the adjacent piston, *F*, in the chamber *B*, thus causing the revolution of the rotary head in the direction of the arrow, Fig. 85 1, the said piston-chamber will be brought to the exhaust-port *y*, from which the operating-fluid will pass through the passage *z* into the chamber *d* of the outer case, and from the chamber *d* the said operating-fluid will pass 90 out at the passage *c*. The pistons *F* are hollowed upon their faces *a'* to conform to the curvature of the stationary valve *C*, thus preventing clearance waste of steam in running the engine, which is a very desirable feature 95 in a rapidly-revolving rotary engine. I preferably continue the chambers *B* to the periphery of the stationary valve *C*, whereby the rotary head *D* will be freed from the inwardly-directed pressure of the steam in the piston-chamber, thus greatly reducing the friction 100 and wear in such engines, and in this case the stationary valve *C* serves to form the resisting-head of the piston-chamber.

The spider-plate *g*, which serves to connect the shaft *G* to the rotary head *D*, is cut away at the points *b*² to allow the connecting-rods *m* to pass and form a connection with the eccentric-pin *b*; but such open construction will be rendered unnecessary when the spider-plate is made sufficiently large to extend beyond the extreme limit of the movement of the arms *j*, as shown in Fig. 7, and in this case the connecting-rods *m* and the eccentric-pin *b* will be held in a chamber, *c*', between the spider-plate and the face of the rotary head *D*, and a proper perforation, *d*', can be made at any desirable point in the spider-plate for the passage of the steam or other operating-fluid from the chamber *c*' to the chamber *d* of the outer case.

In the foregoing description of my invention I have described the steam or other operating-fluid as passing in at the pipe *H* and out of the passage *c* in the base *b*; but it is evident that a rotary movement of the piston-head *D* will be produced in a reverse direction if the operating-fluid is made to enter at the said passage *c* and exhaust from the said pipe *H*. Therefore either the live or exhaust steam may be made to occupy the chamber *d* of the outer case, as desired.

I claim as my invention--

1. In a rotary engine, the combination, with the stationary valve provided with inlet and exhaust ports and the eccentric-pin, of the rotary head fitting the periphery of the said valve and provided with radially-directed piston-chambers, the reciprocating pistons operatively connected to the eccentric-pin, the spider-plate attached to the rotary head, and the shaft extending outward from the spider-plate, substantially as described. 30 35

2. In combination, an outer case provided with inlet and outlet passages for the operating-fluid, a stationary valve extending inward from one head or end of the outer case, and provided with ports, one of which is in communication with the chamber of the outer case, the eccentric-pin, a rotary head fitting the periphery of the valve and provided with radially-directed piston-chambers, the pistons fitting the said piston-chambers and operatively connected with the eccentric-pin, the spider-plate attached to the rotary head, and the shaft extending outward from the spider-plate, substantially as described. 40 45 50

CHARLES H. CARY.
